UNITED STATES PATENT OFFICE

JOHN L. SOMMER, OF NEWARK, NEW JERSEY.

DESIGN FOR A HAMMER.

SPECIFICATION forming part of Design No. 27,949, dated December 7, 1897.

Application filed August 9, 1897. Serial No. 647,640. Term of patent 7 years.

To all whom it may concern:

Be it known that I, JOHN L. SOMMER, a citizen of the United States, and a resident of Newark, in the county of Essex and State of New Jersey, have invented a new and original Design for Hammers, of which the following is a specification.

This invention consists in a novel shape for a hammer substantially as herein shown and described.

In the drawings annexed, Figure 1 is a side elevation, and Fig. 2 an edge view, of a tool embodying the present design.

The tool is shown formed of a rod having one end portion bent into the shape of the letter **U** and disposed transversely of and continuously with the adjacent portion, which latter is flattened to form a long wedge-shaped handle *a* for the hammer, of which

the opposite end portion constitutes the head *b*. The reflex bend in the rod composing the tool confers the necessary excess of weight of the head over that of the handle for giving the tool the required balance, while the gradual flattening of the handle portion from a point near the head to the opposite extremity gives the requisite width for the easy grasp of the hand of the user.

What I claim is—

The design for a hammer substantially as herein shown and described.

Signed at Newark, in the county of Essex and State of New Jersey, this 7th day of August, A. D. 1897.

JOHN L. SOMMER.

Witnesses:

LOUISE KRICHBAUM,
HENRY J. MILLER.
